UNITED STATES PATENT OFFICE.

CHARLES H. CROWELL, OF BROOKLYN, NEW YORK.

CORRUGATED-PAPER BOX OR OTHER CONTAINER.

1,299,683.

Specification of Letters Patent.

Patented Apr. 8, 1919.

Application filed June 21, 1917. Serial No. 176,011.

To all whom it may concern:

Be it known that I, CHARLES H. CROWELL, a citizen of the United States, and resident of the borough of Brooklyn, county 5 of Kings, city and State of New York, have made a certain new and useful Invention Relating to Corrugated-Paper Boxes or other Containers, of which the following is a specification, taken in connection with the 10 accompanying drawing, which forms part of the same.

This invention relates especially to the closing and sealing of corrugated paper boxes or other generally similar containers 15 by which their end flaps are strongly and reliably held together and secured in place in connection with the sides of the container. For this purpose the usual outer seam between the substantially meeting edges of 20 the outer pairs of end flaps may be sealed by an inner sealing strip of gummed paper or cloth tape or other adhesive material which may be secured along the inner face of this seam next the end of the container, this strip preferably having its ends doubled back 25 over the outer faces of this flap seam so as to form locking ends securing the flaps still more strongly at their edges so that tearing cannot so readily start at these points. 30 An outer sealing strip may also be advantageously used and such a strip of similar adhesive material which is preferably somewhat wider than the inner sealing strip may be pasted and rubbed down along the outer 35 face of this flap seam so as to hold the same together and reinforce the doubled back locking ends of the inner sealing strip, if desired. It is advantageous to have this outer sealing strip formed with projecting 40 securing ends which adhesively engage the adjacent sides of the container so as to hold the end flaps securely thereto.

In the accompanying drawing showing in a somewhat diagrammatic way an illustrative embodiment of this invention,

Figure 1 is a perspective view of a partly closed container of which portions have been broken away for greater clearness.

Fig. 2 is another perspective view thereof

when the container has been still further 50 closed and sealed.

Fig. 3 is a partial transverse section through the container substantially along the line 3—3 of Fig. 2; and

Fig. 4 is another similar partial section 55 taken along the line 4—4 of Fig. 2.

The container formed of pasteboard or corrugated paper box board may be of any suitable type and construction and provided with meeting or overlapping pairs of end 60 flaps of any suitable description. As indicated the container may be formed of corrugated box board having the sides 1 and the connected end flaps 3, 4 separated by the usual slots or cut-out portions 15. It 65 is desirable to reinforce the creased or scored folding edges of such a container by applying to the corrugated paper box board blank suitable inner reinforcing strips, such as 10, 11 of strong gummed paper or cloth tape 70 which may be adhesively secured to these folding edges or creased seams at any stage 75 of the manufacturing operation. In this way by using, for instance, 60 or 90 pound Kraft paper tape the ordinary corrugated box board may be so reinforced along the folding edges of the blank so that the usual creased seam at this point is sufficiently strengthened to have substantially or fully 80 the strength of the body of the blank. If desired, the reinforcing strips 10 extending around the seam between the sides of the box blank and the connected end flaps thereof may first be put in place and then the other inner reinforcing strips 11 may be 85 applied, although of course this order may be reversed if more convenient. A similar inner reinforcing strip 20 of gummed paper or cloth tape may be applied to the side seam edges 13 and 18 of the blank at any desired 90 stage of its manufacture and the outer connecting strip 14 preferably of gummed cloth tape may close this side seam on the outside. These inner reinforcing strips 11 may 95 be forced into the creased or scored folding edge of the blank at the point 12 in some cases and are also advantageous in prevent-

ing any leakage of the contents of the container into these folding edges in addition to their important strengthening action. The use of such inner reinforcing strips 5 which is described and claimed in my co-pending application is not, however, necessary in all cases, although highly desirable where the container is formed of corrugated paper box board.

10 In closing the end flaps of the container the inner flaps 4 may be folded together as indicated in dotted lines in Fig. 1 so that their substantially meeting and abutting edges may form a flap seam, such as 9. The 15 outer end flaps 2, 3 may then be folded together so as to form between their preferably meeting and abutting edges a substantially closed outer flap seam 8. These flaps may be advantageously connected by the use 20 of sealing strips of gummed paper or cloth tape and an inner sealing strip may be advantageously applied and secured to the outer pair of end flaps as they are being closed together. For this purpose the inner 25 sealing strip 5 may have its upper gummed surface rendered adhesive as by moistening the same and may be laid in position before the end flaps 2 and 3 are folded together and down upon this sealing strip which is thus 30 adhesively secured thereto. It is also desirable to have this inner sealing strip formed with projecting ends, such as 6, 7, which may then be advantageously folded or doubled back over the outer surfaces of 35 these end flaps so as to be adhesively secured thereto and constitute locking ends which still more strongly hold the end flaps together at either end of the seam and thus prevent the tearing or parting of these flaps 40 which usually starts at these points.

Although not necessary in all cases it is desirable to also use an outer sealing strip which may advantageously be a wider strip of gummed paper or cloth tape 17 which 45 may be applied to the outer flap seam after its gummed lower surface has been moistened and rendered adhesive so that it can be adhesively secured and rubbed down upon this flap seam and the locking ends of the 50 inner sealing strip as indicated in Fig. 2. This outer sealing strip is preferably provided with projecting securing ends 16 which may be folded down and adhesively secured to the adjacent sides 1 of the container 55 as indicated so as to strongly and securely hold the adjacent portions of the end flaps in proper co-operation therewith. These sealing strips may of course be readily moistened by any suitable or usual moistening 60 machines and may be applied and smoothed or rubbed down by the operators during the preliminary closing of the end flaps at one end of the container as indicated in Fig. 1 when this end of the container may of course

be supported by a form or support located 65 within it. And after being filled the end flaps at the other end of the container or package may be closed and sealed as above described, so that a strong package is secured which has the additional protection 70 against tampering which is provided by the inner sealing strip with its locking ends which form additional safeguards against opening or tampering with the package in such a way as not to be instantly apparent. 75

This invention has been described in connection with a number of illustrative forms, proportions, shapes, sizes, materials, arrangements, parts and methods of manufacture and use, to the details of which disclosure 80 the invention is not of course to be limited, since what is claimed as new and what is desired to be secured by Letters Patent is set forth in the appended claims.

1. The corrugated box board container 85 formed with end flaps having substantially abutting edges, a plurality of end flaps being sealed by an inner sealing strip of tape adhesively secured to the inner faces of the seam between such end flaps and having 90 doubled back locking ends folded around and secured to the outer faces of said seam adjacent its ends and an outer sealing strip of wider tape adhesively secured to the outer faces of said flap seam and overlapping and 95 secured to said locking ends of said inner sealing strip.

2. The corrugated box board container formed with end flaps, one of the outer pairs of end flaps being sealed by an inner 100 sealing strip of gummed paper tape adhesively secured to the inner faces of the seam between such end flaps and having doubled back locking ends folded around and secured to the outer faces of said flaps 105 adjacent the seam, and an outer sealing strip of tape adhesively secured to the outer faces of said flaps and overlapping and secured to said locking ends of said inner sealing strip.

3. The container formed with end flaps, one of the pairs of end flaps being sealed by an inner sealing strip of tape adhesively secured to the inner faces of the seam between such end flaps and having a doubled 115 back locking end, folded around and secured to the outer faces of said flaps adjacent the seam.

4. The paper box formed with end flaps having substantially abutting closely meeting edges, each of the outer pairs of end flaps being sealed by an inner sealing strip of gummed paper tape adhesively secured to the inner faces of the seam between such end flaps and having doubled back locking 120 ends folded around and secured to the outer faces of said seam adjacent its ends and an outer sealing strip of gummed paper tape 125

adhesively secured to the outer faces of said flap seam and overlapping and secured to said locking ends of said inner sealing strip.

5. The paper box formed with end flaps having substantially abutting edges, one of the outer pairs of end flaps being sealed by an inner sealing strip of gummed tape adhesively secured to the inner faces of the

seam between such end flaps and having doubled back locking ends folded around 10 and secured to the outer faces of said seam adjacent its ends.

CHARLES H. CROWELL.
